INTERNAL COMBUSTION MOTOR

Karl W. Rohlin, Dover, Del.

Application August 30, 1937, Serial No. 161,703

14 Claims. (Cl. 123—52)

My invention relates to internal combustion engines of the explosion type and comprises a combination operative structure which includes motor portions of different thermodynamic cycles.

5 In carrying out my invention I connect a single crank shaft with a group of cylinders of the four-cycle type and a group of cylinders of the two-cycle type. Such four-cycle motor portion may include four cylinders and may be employed as the primary driving means, firing continuously and producing power when the structure is operating; while the two-cycle motor portion may include two cylinders, which motor portion may be cut into and out of firing service as power requirements demand.

10 The operation of four cylinders of a four-cycle motor imparts a power impulse every 180° movement of the crank shaft, and a six-cylinder, four-cycle motor imparts an impulse every 120°. The object of my present invention is to provide means whereby I can utilize motors of dissimilar cycles for driving a common crank shaft; the primary and secondary motors being coordinated to secure eight-cylinder performance and provide power impulses every 90°, with the use of only six cylinders.

15 A particular merit of my invention resides in the fact that it provides for the use of the efficient and reliable four-cycle type of motor for the primary or continuous firing portion, while permitting use of the more powerful two-cycle motor for the secondary or intermittently firing portion. By proper correlation of these two motor structures, fewer pistons move to cause 20 friction during the whole time the combination motor operates so that the overall efficiency of the same is greater than that of conventional motors despite the fact that its two-cycle portion may indicate slightly lower thermal efficiency.

25 40 In order to coordinate the two portions of the combination motor structure, each having a different thermodynamic cycle, I may make use of the method and apparatus described in my earlier application, filed December 18, 1936, Serial No. 116,464, and I am able to obtain all the 30 benefits of economy, etc., resulting from the use of that invention. The four-cycle cylinders fire whenever the power required of the motor is moderate or low, and the two-cycle cylinders are automatically brought into firing service by mechanism similar to that set forth in my earlier application, whenever high power is required of the motor, or when it runs slowly.

35 45 In addition, I have devised another coordinat-

ing feature designed to harmonize the power output of each of the two motor portions of different cycles comprising pressure controlling means which forms an important part of the present invention.

5 The method and means described in my application above referred to provided for coordinating the operation of two portions of an internal combustion engine. My present invention provides for coordinating two portions of a motor 10 of different thermodynamic cycles.

A feature of my invention is the provision of a combination motor having one portion of a type that may be readily put into operation with conventional starting mechanism, while the remaining portion of the motor may be of a type 15 that is more or less difficult to put into initial service, such as the two-cycle portion.

A further feature of my invention is the use 20 of the flexibles, readily controlled, four-cycle portion of the motor during periods when little power is required and the fuel-supply is partially throttled.

A further feature resulting from the inclusion 25 of the powerful two-cycle portion of the combination motor structure is the ability to reduce motor speed without reducing power output. A motor designed in accordance with my present invention can be operated at three-fourths of the speed of a conventional motor of the same 30 size and produce as much power. As a result, the mechanical efficiency of the combination motor structure may be appreciably increased and, in addition, many or all of the benefits or advantages now ascribed to the commercial device 35 known as the "overdrive", are present.

A further feature, resulting from the reduced 40 motor speed and reduced internal friction, and elimination of suction vacuum on all but four of the cylinders during light load conditions, provides much of the benefits attributed to "free wheeling."

45 And a still further feature disclosed by tests of a practical model designed according to the invention of the application above referred to, is retained in one form of the present structure; namely: heat delivered into the jacket water is reduced by firing only part of the cylinders most of the time and air passing through the non-firing cylinders serves to cool the motor 50 structure so that the entire cooling load of the structure is reduced sufficiently to permit, in some cases, elimination of the radiator fan and cooling-water circulating pumps at present required in conventional motors.

In general, this invention may be best carried out by including a group of four-cycle cylinders of twice the number of the two-cycle cylinders; such arrangement having the merit that each of the two portions of the motor will produce substantially one-half the power. This relation enables the intermittently firing cylinders to fire intermediate the firing of the continuously firing cylinders so that maximum smoothness and minimum vibration result when all of the cylinders fire.

Many arrangements of cylinder grouping are within the scope of my invention. In the following description reference is made to a combination motor structure involving the use of six cylinders in line; two of which are of the two-cycle type while the rest are of the four-cycle type. Many other arrangements are possible; for instance, the four-cycle cylinders might form one arm of a V while the two-cycle cylinders could form the other arm; such arrangement being equivalent to a conventional eight-cylinder motor. Or, nine cylinders placed in line, six of four-cycle type and three of two-cycle type, would fire like, and be equivalent to, a conventional twelve-cylinder motor. Or, in lieu of this, such nine-cylinder motor could be arranged with six cylinders on one arm of a V and three cylinders on the other arm.

These and other features of my invention are more fully set forth hereinafter; reference being had to the accompanying drawings, more or less diagrammatic in character, in which:

Figure 1 is a view in elevation, partly in longitudinal section, of a combination motor structure within the scope of my invention.

Fig. 2 is a cross-sectional view on the line II—II, Fig. 1.

Fig. 3 is an enlarged sectional view of one of the carburetors, taken on the line III—III, Fig. 2.

Fig. 4 is a sectional view on the line IV—IV Fig. 2.

Fig. 5 is an enlarged sectional view on the line V—V, Fig. 1, illustrating blower mechanism employed with my improved motor structure.

Fig. 6 is a fragmentary plan view, in section on the line VI—VI, Fig. 2.

Fig. 6a is a diagrammatic view illustrating the air flow channels to the two-cycle cylinders of the motor structure.

Fig. 7 is an enlarged sectional view of control mechanism which I may employ.

Fig. 8 is a diagrammatic view of the ignition distributor and its wiring.

Fig. 9 is a graph showing the ratio of pressure drops through the carburetors, and

Fig. 10 is a diagrammatic view showing part of the electrical system of a vehicle such as an automobile, including the interconnected wiring for the control mechanism shown in Fig. 7 and forming part of this invention, as well as that of my companion application, filed August 30, 1937; the electrical portion thereof being substantially identical with that shown in Fig. 7 of said companion application, Serial No. 161,702.

As in the structure forming the subject of my co-pending application filed Dec. 18, 1936, Serial No. 116,464, and in that of my companion application, reference is made to manifold channels M and N which feed separate sets of cylinders. In the present instance the manifold channel M communicates with the group of continuously firing cylinders constituting the four-cycle portion of the combination motor, while the manifold channel N communicates with the cylinders

of the two-cycle portion of the motor, which fire intermittently.

The combination motor illustrated in Fig. 1, comprises four cylinders of the four-cycle type, indicated at 1, 2, 3 and 4, and constituting the continuously firing portion of the motor, and two cylinders, indicated at 5 and 6, which constitute the two-cycle portion thereof; the latter being mounted forward of the four-cycle cylinders. The connecting rods for the pistons of the several cylinders are indicated at 1^r, 2^r, 3^r, et seq., and are joined with a crank shaft 7 in the usual manner. The cylinders may be formed in a unitary block, and the crank shaft and the connecting rods for the several pistons are housed by an oil pan indicated at 8. A conventional flywheel is indicated at 9. The usual exhaust manifolds, piping, etc., common to engines of the four-cycle and two-cycle type, are not shown. Other auxiliaries, such as the generator, fuel pump, oil pump, fan and water pumps (if used) are omitted from the drawings for the purpose of simplification.

The crank shaft which I employ with my combination motor will differ from an ordinary crank shaft for a six-cylinder motor wherein explosions take place every 120° of its movement. In the present instance the crank shaft may be of any usual cast-iron type, similar to that used in a Ford V-8 motor, and may consist of disk-like portion 7^a joining crank throws 1^a, 2^a, 3^a, 4^a, 5^a and 6^a. In Fig. 1, crank throw 1^a is shown in the extreme rearward position; crank throws 2^a and 3^a in their extreme forward positions; crank throw 4^a in the extreme rearward position; crank throw 5^a in the lowest position, and crank throw 6^a in the highest position. Crank throws 5^a and 6^a are disposed at right angles to crank throws 1^a, 2^a, 3^a and 4^a, and the latter are arranged in the usual manner for four-cylinder, four-cycle engines.

Operation of the separate portions of the combination motor structure is controlled by a series of suction and exhaust valves; those for the four-cycle cylinders being actuated by cams of usual type carried by a cam shaft 10, and indicated at 10^a, while the suction valves of the two-cycle cylinder are actuated by double cams 10^b, also carried by said cam shaft. The cam shaft is driven at one-half the speed of the crank shaft by timing gears 7^c and 10^c, mounted on the ends of the crank shaft and cam shaft, respectively.

Intake valves for the cylinders 1, 2, 3 and 4, are indicated at 1^s, 2^s, 3^s, and 4^s, and exhaust valves for said cylinders are indicated at 1^x, 2^x, 3^x, and 4^x. The intake valves for the cylinders of the two-cycle portion of the motor are indicated at 5^s and 6^s. Such cylinders, as is well known, exhaust through ports in the side walls of the cylinders, one of which is shown in the sectional view, Fig. 2, and indicated at 5^x. The several cylinders are fired in turn by a conventional ignition system, including a distributor such as illustrated in Fig. 8, which may be mounted on the front end of the cam shaft.

Independent carbureting means, preferably housed in common or adjacent casings, and indicated at 11 and 12, communicate with the manifold channels M and N, respectively, which deliver to the four-cycle and the two-cycle portions of the motor, respectively. The carburetors may be fitted with air cleaning devices, idling jets, and other features commonly employed.

In starting my improved combination motor, the four-cycle portion normally fires first and puts the entire structure in operation. If at 75

such time the control (hereinafter described) is so positioned as to fire the four-cylinder portion only, then such portion will function in the usual manner and while the parts of the two-cycle portion will be in motion, they will not deliver power. When so running, the vacuum produced by the suction strokes of the pistons of the four-cycle portion draws air into choke chamber 11^a of carbureter 11, which passes thence through Venturi tube 11^b, where it mixes with fuel entering via channel 11^c from a metering jet 11^d, in passing from float chamber 11^e. The fuel in chamber 11^e enters at 11^f from a suitable source past a float-controlled valve 11^g. The pressure of the air and vapor in choke chamber 11^a is equalized with that in float chamber 11^e through pipe 11^h, with the result that the flow of air and fuel through Venturi tube 11^b are both proportional to the drop in pressure between choke chamber 11^a and the Venturi tube.

Passage of the fuel-air mixture to the manifold channels M and N is controlled by throttle valves 13 and 14, mounted on shaft 15, journaled in the manifold walls below the Venturi tubes; the opening of these throttle valves being controlled by the accelerator pedal and by the control about to be described. Such fuel-air mixture for the four-cycle portion of the motor then passes through manifold channel M to suction valves 1^s, 2^s, 3^s and 30 4^s, as said valves are operated in turn by the cams 10^a.

The cylinders of the two-cycle portion of the motor receive fuel and air under control of the intake valves 5^s and 6^s, which are operated in 35 turn by the dual cam lifts 10^b mounted on the cam shaft 10; the respective pistons uncovering the exhaust ports in the walls of their cylinders (one of which is shown at 5^x in the sectional view, Fig. 2) to relieve and exhaust previously 40 burned gases.

For the purpose of delivering air to the cylinders of the two-cycle portion of the motor, I may provide a blower of the "Root" type, having bladed impellers indicated at 16 and 17, arranged 45 in a suitable housing 18; impeller 16 having two blades and being mounted on the end of the crank shaft 7, while impeller 17 has four blades and is mounted on the end of the cam shaft 10. The impellers fit each other and the housing in 50 such manner as to avoid friction and without leaking any appreciable amount of air; thereby eliminating power loss. The impellers move in the direction of the arrows, and displace air under moderate pressure from the intake 18^a to the outlet 18^b, and, if desired, the intake may be 55 fitted with suitable air cleaning and silencing devices. As the speed of the motor increases, the speed of the impellers also increases and effects delivery of more air for use in cylinders 5 and 6; automatically proportioning to some extent 60 the amount of air delivered to the amount required in said cylinders. To insure the delivery of fuel charges of substantially the same volume into the two-cycle cylinders 5 and 6, as is delivered into the four-cycle cylinders 1, 2, 3 and 4, so that the power impulses from all six firing 65 cylinders will be substantially the same in force and smooth motor operation will result, a pressure regulator (hereinafter described) is coordinated with the carbureter 12, and with the cylinders 5 and 6 and their valves and ports. Further regulation of the air delivered to cylinders 5 and 70 6 is provided by the carbureter valve and by the pressure regulator.

75 From outlet 18^b, air delivered by the blowers is

conducted via tube 18^c to butterfly-valve assembly 19, which comprise a pair of butterfly valves 19^a and 19^b, mounted on a common shaft 19^c journaled in the walls of the passages and operatively connected to control mechanism (to be 5 later described) by means of a link 19^d. From channel 18^c such air passes to channel 19^e directly communicating with choke chamber 12^a of carbureter 12, and its pressure is further controlled by regulator 20, comprising a pair of 10 bellows-folded elements 20^a and 20^b mounted above and to one side of said choke chamber, which elements operate a butterfly escape valve 20^c, by means of rod 20^d. The inner space 20^e of bellows 20^b is in free communication with air 15 channel 20^f of the regulator 20.

The annular space 20^g between the bellows-folded elements 20^a and 20^b communicates via tube 20^h with intake manifold M and the vacuum produced therein by the "pumping effect" of the 20 pistons of the four-cycle portion of the motor acts to draw the head 20ⁱ of the bellows assembly inwardly. The blower pressure in air channel 20^f tends to move the head 20ⁱ of the bellows assembly outwardly, and will in fact do so whenever 25 that pressure is excessive; lifting rod 20^d to open valve 20^c so as to permit some of the air to escape to the atmosphere and lower the pressure in air channel 20^f.

The degree of pressure maintained by the regulator 20 depends upon the vacuum in manifold channel M and on the proportional areas of the two bellows elements. The curves indicated by the graph shown in Fig. 9, represent generally the variations in such pressures for the full range 35 of throttle positions if the effective area of bellows element 20^a is approximately one and one-half times the effective area of bellows element 20^b, in which case the pressures indicated at p and p' and maintained in air channel 20^f and 40 carbureter 12 by the pressure regulator 20 will be one-half as much above atmospheric pressure as the vacua in manifold channel M and indicated v and v' are below the atmosphere. Venturi tube 12^b and metering jet 12^d are proportioned to deliver the requisite quantity of 45 fuel, and throttle valve 14 mounted on shaft 15 is proportioned to deliver the requisite amount of fuel-air mixture under this scale of pressures; taking into consideration the pulsating nature of 50 flow through such carbureter, particularly when it is applied to two cylinders of the two-cycle type.

It will therefore be seen that pressure regulator 20 maintains through carbureter 12 and 55 butterfly throttle valve 14 a scale of pressure drops that are definitely proportional to the pressure drops through carbureter 11 and butterfly throttle valve 13; the pressures in the first instance being entirely above the atmosphere. 60 When driving conditions cause a large pressure drop through carbureter 11 in its throttled condition feeding the continuously firing cylinders of the four-cycle portion of the motor, a proportionately large pressure drop will be created 65 through carbureter 12 in its throttled condition feeding the intermittently firing cylinders of the two-cycle portion of the motor, and vice versa.

By mounting the throttle valves 13 and 14 on 70 the same shaft, the same angular opening of both valves is insured, and likewise proportional areas through them, for all throttle positions. The flow of air and fuel through both carbureters 11 and 12 is therefore proportional for all driving 75

conditions during six-cylinder firing so that the delivery of fuel to each group of cylinders is proportional to their requirements and the resulting power impulses are substantially equal and uniform. And the power output of my improved motor closely approximates that of a conventional eight-cylinder motor of similar bore and stroke.

The above-described means for equalizing fuel and air delivery to both sets of cylinders enables power compensation mechanism, such as that described in my companion application but not shown in the accompanying drawings, to operate effectively; such mechanism maintaining the power output substantially constant when the cylinders of the two-cycle motor section are cut into or out of firing service.

In the present instance I have shown in Figs. 1 and 7; the latter view being in detail; a form of control mechanism substantially like that illustrated in my co-pending application before referred to but differing from that of my companion application filed of even date herewith in that the piston element of the present control device is actuated pneumatically while the piston element of my companion application is actuated hydraulically. In the present instance a bored block 22 supports a bellows element 22^a, and a solenoid coil 22^b; the latter having a movable armature 22^c which is raised and lowered to affect the position of a piston element 23 which in turn controls the operation of the combination motor structure. A chamber 23^a is disposed below the block 22 within which the piston element 23 is movably mounted and the latter is moved by the vacuum in manifold channel M communicating via tube 22^d with the passages 22^e and 22^f in the block 22; inlet and exhaust from such passages being controlled by valve portions 22^g and 22^h carried by the solenoid armature.

Whenever the speed of the battery charging generator is high enough to cause the cut-out to close its switch, and whenever the vacuum in manifold channel M is high enough to affect the bellows element 22^a and close switch 22^s, provided that at the same time the clutch pedal is up, coil 22^b will be energized and will lift the armature 22^c; the valve portion 22^g thereof being moved in position to connect passage 22^e with tube 22^d, and the valve portion 22^h being moved to position to connect passage 22^f with a passage 22^j leading to the atmosphere and permit piston 23 to move to the left. If the generator speed falls low enough to open the cut-out, or if the load on the motor increases enough to reduce the vacuum in manifold channel M to the point where switch 22^s opens, or if the clutch pedal is depressed, then the circuit to coil 22^b will be broken and armature 22^c will fall. In such position valve portions 22^g and 22^h connect passages 22^e and 22^f, in the manner shown in Fig. 7 wherein the piston is at the right of the chamber 23^a.

When control 22 functions to cut the cylinders of the two-cycle portion of the motor out of firing service, its piston 23 moves to the left, drawing down lever 22^k and effecting, through link 19^d, rotation of valve shaft 19^c, counter-clockwise. Butterfly valve 19^b is then closed, preventing air flow through carbureter 12, and delivery of fuel thereby. Butterfly valve 19^a, also mounted on shaft 19^c, moves from its previously closed position to wide open position so that all of the air delivered by the blower, except that passing valve 20^c, will be by-passed around carbureter 12 via channel 19^e directly into manifold channel N for

passage to cylinders 5 and 6 whenever intake valves 5^a and 6^a are opened; such air simply serving to cool these cylinders during their non-firing periods.

Rotation of valve-carrying shaft 19^c operates 5 the compensation mechanism above referred to, part of which is mounted on said shaft, to maintain uniform power output during the change from six to four cylinders in firing service.

When control 22 operates to effect the firing of 10 six cylinders, piston 23 moves to the right, as indicated in Fig. 7, link 19^d is raised, shaft 19^c rotates clockwise, butterfly valve 19^a is closed to prevent direct delivery of air through channel 19^e to manifold N for passage to cylinders 5 and 6, 15 and butterfly valve 19^b is opened to permit delivery of fuel and air from carbureter 12 to these cylinders under control of throttle valve shaft 15 and pressure regulator 20.

Each of the carbureters 11 and 12 contain a 20 Venturi tube, indicated at 11^b and 12^b; separate metering jets 11^d and 12^d; separate float chambers 11^e and 12^e, with separate floats, and separate needle valves 11^f and 12^f, for controlling the admission of fuel to float chambers 11^e and 12^e, and separate equalizing pipes 11^h and 12^h for equalizing the respective float and choke chambers.

For the purpose of firing the fuel charges in the cylinders at the proper time and in the proper order, I may employ distributing means such as 30 shown in Fig. 8 having a distributor arm 25 which may be mounted on and driven by the cam shaft 10; said arm delivering high voltage current to contacts 1^b, 2^b, 3^b, et seq., which are so wired to the spark plugs, indicated at 1^c, 2^c, 3^c, et seq., that, 35 in the present instance, the cylinders fire in the following order, viz: 1, 6, 2, 5, 4, 6, 3, 5. To effect this firing order in a six-cylinder combination motor structure of the type forming the subject of my invention, a distributor for an eight-cylinder, 40 four-cycle, motor may be used, with two of its eight high tension leads connected in pairs to each of the spark plugs 5^c and 6^c. The other four leads will be connected to the spark plugs 1^c, 2^c, 3^c, and 4^c singly in the conventional manner.

The crank shaft and the distributor mechanism will coordinate to deliver one power impulse for each 90° movement of the crank shaft when all cylinders fire, so that the operation of the motor structure of my present invention will substantially equal in smoothness and power output the 50 conventional eight-cylinder, four-cycle motor, in which explosions normally occur every 90°. During periods of reduced load, when the controlling mechanism operates to fire four cylinders only, the firing order will be 1, 2, 4, 3; cylinders 5 and 6 55 being out of firing service. Explosions and power impulses then occur every 180°, just as they do in a conventional four-cylinder, four-cycle motor.

Provided the clutch pedal switch is closed, 60 armature 22^c will always be raised when the accelerator pedal is in its highest or idling position. When coil 22^b is energized to raise armature 22^c, piston 23 will be drawn to the left to position butterfly valves 13 and 14 to fire four cylinders. When coil 22^b is not energized, armature 22^c will fall by gravity and piston 23 will be drawn by the vacuum to the right, to position butterfly valves 13 and 14 to fire six cylinders.

The control device of my present invention includes means designed to avoid flutter of the operating mechanism when it passes from four-cylinder to six operation and vice versa, and other means designed to avoid chatter of the vacuum switch; both being similar to that shown in my 70

companion application filed of even date herewith. A lever 22^m mounted on the control device and having one end actuated by an eccentric 22ⁿ on the piston shaft, through a lever 22° and a connecting link 22^p, constitutes the non-flutter means, and actuation of the other end of lever 22^m by the armature 22^c constitutes the means for avoiding chatter. When piston 23 moves to the left to position the mechanism to fire four cylinders, eccentric 22ⁿ moves lever 22°, raising link 22^p and the outer end of lever 22^m to which it is connected; thereby resetting the point at which switch 22^s may be operated by bellows 22^a so that piston 23 will not return to its six-cylinder firing position without a considerable change in the vacuum affecting bellows 22^a. In this manner an immediate return of the mechanism to the six-cylinder position, or flutter, is avoided.

Lever 22^m is also raised by armature 22^c whenever switch 22^s has made sufficient contact to energize coil 22^b to lift the armature, this movement making a more positive contact in switch 22^s so that coil 22^b will continue to be energized so as to hold armature 22^c up and avoid chatter. If contact 22^s breaks, even momentarily, permitting armature 22^c to fall, lever 22^m moves downward and switch 22^s is positively opened, thereby preventing chatter in this instance.

Shaft 24 mounted in the choke chambers carries butterfly valves 11^j and 12^j arranged to "choke" the air flow to the respective carburetors for the purpose of enriching the fuel-air mixture whenever the temperature of the motor is subnormal. The position of shaft 24 may be adjusted by means of a lever 25 connected by suitable linkage with the instrument board of the automobile.

The air delivered by the blower is transmitted from space 19^e of butterfly valve assembly 19 via channels 19^g and 12^k to space 20^f which is in free communication with choke chamber 12^a of carburetor 12.

The control mechanism illustrated in Fig. 7 is coordinated with the electrical generator b, battery B, and switches I, C and A, by means of the wiring system shown in Fig. 10, which is fully described in my companion application filed of even date herewith, Serial No. 161,702, and hereinbefore referred to.

Operation of the generator G by the engine forming the subject of this invention below some predetermined speed, will not energize magnetic cutout M sufficiently to attract armature M' and close switch M², so that the electrical circuit through coil 22^b will not be energized (except through accelerator pedal switch A, if such switch is closed), armature 22^d will remain in its lower position, and piston 23 will be positioned so that six cylinders fire. When, however, generator G is driven fast enough to generate sufficient voltage to energize magnetic cutout M sufficiently to attract armature M' so as to close switch M² and complete the circuit through coil 22^b (provided clutch switch C is closed), and provided the load on the engine is light enough to operate under a relatively high vacuum in intake manifold M so as to shorten bellows element 22^a and close switch 22^s, armature 22^d will then be raised and piston 23 will be moved to the left to position shaft 19^c to fire four cylinders.

If, however, the load on the engine is increased by depressing accelerator pedal A so as to open butterfly valve 13, or by the vehicle encountering a hill, etc., the vacuum in the manifold M will be reduced, bellows 22^a will expand, switch 22^s

will be opened, coil 22^b will no longer be energized, armature 22^d will fall, piston 23 will move to the right and six cylinders will fire. Similarly, when the engine and the generator speed are reduced sufficiently, switch M² will be opened, coil 22^b will no longer be energized and six cylinders will fire. Opening switch C will break the circuit through armature 22^b and fire six cylinders. Closing switch A will energize coil 22^b under any conditions of load and speed, and four cylinders 10 only will fire. The use of switches A and C is optional.

As in my companion application, Serial No. 161,702, magnetic cutout M includes coil M³ designed to prevent flutter, and control 22 includes eccentric 22ⁿ, lever 22°, link 22^p, and lever 22^m, designed to prevent flutter; all of which elements are described in detail in the application just referred to.

It should be understood that the method and means described in my companion application filed of even date herewith may also be used in lieu of the mechanism above described to cut the two-cycle portion of the combination motor into and out of firing service. Such mechanism may be operated hydraulically as described in said companion application and would control the position of adjustable push rods normally serving to actuate intake valves 5^s and 6^s; causing these valves to function in the conventional manner during periods when six cylinders fire, and automatically shortening said rods to permit valves 5^s and 6^s to remain seated when only four cylinders fire. In this case the air delivered by the blower would be discharged freely to the atmosphere past butterfly valve 19^e, whose discharge port would have no connection with the manifold passage N. Such air therefore could not serve to cool the non-firing cylinders as it would in the arrangement shown in the drawings herein and as above described.

It will be understood that various modifications may be made in the foregoing embodiments of my invention without departing from the spirit and scope of the same as set forth in the appended claims.

I claim:

1. A motor structure of the internal combustion type comprising a group of four-cycle cylinders and a group of two-cycle cylinders, pistons in said cylinders, a crank shaft operatively connected to all of said pistons, and means responsive to speed for cutting the two-cycle portion of the motor into and out of firing service.

2. A motor structure of the internal combustion type comprising a group of four-cycle cylinders and a group of two-cycle cylinders, pistons in said cylinders, means for feeding fuel charges to said cylinders, a crank shaft operatively connected to all of said pistons, and means coordinated with the delivery of smaller fuel charges to the four-cycle cylinders for cutting the two-cycle cylinders out of firing service.

3. A motor structure of the internal combustion type comprising a group of four-cycle cylinders and a group of two-cycle cylinders, pistons in said cylinders, means for feeding fuel charges to said cylinders, a crank shaft operatively connected to all of said pistons, and means responsive to increased speed and coordinated with the delivery of smaller fuel charges to the four-cycle cylinders for cutting the two-cycle cylinders out of service.

4. A motor structure of the explosion type comprising a group of four-cycle cylinders and a

- group of two-cycle cylinders, pistons in said cylinders, a crank shaft operatively connected to all of said pistons, and means responsive to vacuum on the four-cycle cylinders for cutting the two-cycle cylinders into and out of firing service.
5. A combination motor of the explosion type comprising a group of cylinders of the four-cycle type and a group of cylinders of the two-cycle type; the latter being one-half the number of the former, means for delivering charges of fuel and air to said cylinders, pistons within said cylinders, a common crank shaft operatively connected with all of said pistons, inlet and exhaust valves associated with the cylinders of four-cycle type, inlet valves associated with the cylinders of two-cycle type, a single cam shaft, single cams on said shaft for operating the valves associated with the four-cycle cylinders, and double cams for operating the valves associated with the two-cycle cylinders.
10. A motor structure of the internal combustion type comprising a group of four-cycle cylinders and a group of two-cycle cylinders under common control, means for delivering fuel charges to said cylinders, pistons in said cylinders, crank shaft connection for said pistons, and means coordinated with the delivery of smaller fuel charges to the four-cycle cylinders for cutting the two-cycle cylinders out of firing service.
15. A motor structure of the internal combustion type comprising a group of four-cycle cylinders and a group of two-cycle cylinders, pistons in said cylinders, carbureting means, an intake manifold for delivering fuel and air to said four-cycle cylinders, crankshaft connection for said pistons, and means responsive to the vacuum in said intake manifold for interrupting fuel delivery to said two-cycle cylinders.
20. A motor structure of the internal combustion type comprising a group of four-cycle cylinders and a group of two-cycle cylinders under common control, means for delivering fuel charges to said cylinders, pistons in said cylinders, crank shaft connection for said pistons, and means affected by the movement of said control for cutting the two-cycle cylinders out of firing service.
25. A motor structure of the internal combustion type comprising a group of four-cycle cylinders and a group of two-cycle cylinders, pistons in said cylinders, carbureting means, an intake manifold for delivering fuel and air to said four-cycle cylinders, crankshaft connection for said pistons, and means responsive to the vacuum in said intake manifold for interrupting fuel delivery to said two-cycle cylinders.
30. A combination motor of the explosion type comprising a group of cylinders of the four-cycle type and a group of cylinders of the two-cycle type; the latter being one-half the number of the former, means for delivering charges of fuel and air to said cylinders, pistons within said cylinders, a common crank shaft operatively connected with all of said pistons, means for increasing the flow of explosive mixture to the four-cycle cylinders when the two-cycle cylinders are out of firing service.
35. A combination motor of the explosion type comprising a group of cylinders of the four-cycle type and a group of cylinders of the two-cycle type; the latter being one-half the number of the former, means for delivering charges of fuel and air to said cylinders, pistons within said cylinders, a common crank shaft operatively connected with all of said pistons, and means for regulating the pressure of fuel mixture before delivery to the two-cycle cylinders in a definite ratio to the pressure of fuel mixture delivered to the four-cycle cylinders.
40. A combination motor of the explosion type comprising a group of cylinders of the four-cycle type and a group of cylinders of the two-cycle type; the latter being one-half the number of the former, separate manifolds for the respective groups of cylinders, means for delivering separate charges of fuel and air to said manifolds for delivery to the respective groups of cylinders, pistons within said cylinders, a common crank shaft operatively connected with said pistons, means for cutting off delivery of fuel and air to the manifold communicating with the two-cycle portion of the motor to put the same out of firing service, and automatic means for increasing the flow of explosive mixture to the four-cycle cylinders when the two-cycle cylinders are out of firing service.
45. A combination motor of the explosion type comprising a group of cylinders of the four-cycle type and a group of cylinders of the two-cycle type; the latter being one-half the number of the former, separate manifolds for the respective groups of cylinders, means for delivering separate charges of fuel and air to said manifolds for delivery to the respective groups of cylinders, pistons within said cylinders, a common crank shaft operatively connected with said pistons, means for cutting off delivery of fuel and air to the manifold communicating with the two-cycle portion of the motor to put the same out of firing service, and automatic means for increasing the flow of explosive mixture to the four-cycle cylinders when the two-cycle cylinders are out of firing service.
50. A combination motor of the explosion type comprising a group of cylinders of the four-cycle type and a group of cylinders of the two-cycle type; the latter being one-half the number of the former, separate manifolds for the respective groups of cylinders, means for delivering separate charges of fuel and air to said manifolds for delivery to the respective groups of cylinders, pistons within said cylinders, a common crank shaft operatively connected with said pistons, means for cutting off delivery of fuel and air to the manifold communicating with the two-cycle portion of the motor to put the same out of firing service, and automatic means for increasing the flow of explosive mixture to the four-cycle cylinders when the two-cycle cylinders are out of firing service.
55. A combination motor of the explosion type comprising a group of cylinders of the four-cycle type and a group of cylinders of the two-cycle type; the latter being one-half the number of the former, separate manifolds for the respective groups of cylinders, means for delivering separate charges of fuel and air to said manifolds for delivery to the respective groups of cylinders, pistons within said cylinders, a common crank shaft operatively connected with said pistons, means for cutting off delivery of fuel and air to the manifold communicating with the two-cycle portion of the motor to put the same out of firing service, and automatic means for increasing the flow of explosive mixture to the four-cycle cylinders when the two-cycle cylinders are out of firing service.
